Primary Examiner — Darlington Ly

(57) **CLAIM**

The ornamental design for a recreational vehicle body as shown and described.

DESCRIPTION

FIG. 1 is a front-right side perspective view of a recreational vehicle body embodying our new design;
FIG. 2 is a rear-left side perspective view thereof;
FIG. 3 is a front elevation view thereof;
FIG. 4 is a right side elevation view thereof;
FIG. 5 is a left side elevation view thereof;
FIG. 6 is a rear elevation view thereof;
FIG. 7 is a top plan view thereof; and,
FIG. 8 is a bottom plan view thereof.

The broken lines in the figures show portions of the recreational vehicle body that form no part of the claimed design.
